A. W. LIMONT.

MACHINE FOR MAKING PROJECTILE BANDS AND THE LIKE.
ORIGINAL FILED NOV. 5, 1915.

Inventor
A. W. Limont,
by *Mary Rockwell*,
his attorney.

UNITED STATES PATENT OFFICE.

ALEXANDER W. LIMONT, OF BRIDGEPORT, CONNECTICUT, ASSIGNEE TO BRIDGEPORT BRASS COMPANY, OF BRIDGEPORT, CONNECTICUT, A CORPORATION OF CONNECTICUT.

MACHINE FOR MAKING PROJECTILE BANDS AND THE LIKE.

Original application filed November 5, 1915, Serial No. 59,840. Patent No. 1,266,963, dated May 21, 1918.
Divided and this application filed July 5, 1918, Serial No. 243,427. Renewed September 7, 1922.
Serial No. 536,801.

To all whom it may concern:

Be it known that I, ALEXANDER W. LIMONT, a citizen of the United States, residing in Bridgeport, county of Fairfield, and 5 State of Connecticut, have invented certain new and useful Improvements in Machines for Making Projectile Bands and the like, of which the following is a full, clear, and exact description.

10 This invention relates to a new machine or press for the manufacture of rifling bands for projectiles, and similar articles. This application is a division of my application Serial No. 59,840, filed November 5, 1915, 15 Patent No. 1,266,963 of May 21, 1918, and it pertains especially to a machine for carrying out the specific process disclosed in my application Serial No. 212,470, filed January 18, 1918, Patent No. 1,275,057 of August 6, 20 1918.

One of the primary objects of the present invention is to provide a simple, convenient and economical form of press or machine for making shell bands of copper or like ductile 25 metal.

Another object of the invention is to furnish a machine or press in which a flat washer of comparatively soft ductile metal, such as copper, may be quickly and accurately 30 drawn into cylindrical shape and then rapidly ejected or discharged.

To these and other ends, the invention consists in the novel features and combinations of parts to be hereinafter described and 35 claimed.

In the accompanying drawing:

Fig. 1 is a fragmentary elevation partly in section of a press embodying my improvements, showing the commencement of the 40 operation; and

Fig. 2 is a similar view showing a later stage of the operation.

Referring to the drawing, I use a blank 10, which is usually in the form of a washer of 45 suitable size cut out of a flat strip or sheet of copper or like ductile material of suitable gauge. The blank 10 is placed in a press, such as shown in Figs. 1 and 2, in which it is drawn to form a cylindrical band. In the 50 example shown, the press has a bed plate 11 with a drawing die 12 mounted therein, said

die being of annular shape and the bed plate having an opening 13 extending through the same in line with the opening 14 of the die, the opening 13 being slightly larger 55 than the opening 14. The drawing die is provided with a cylindrical mouth portion 15 to receive the blank 10 snugly and center the same, and below the cylindrical mouth portion 15, the cylindrical wall of the die 60 is of less diameter, the portions 14 and 15 being joined by an easy curve or fillet. Above the die 12 is a cylindrical drawing punch 16, mounted on a suitable cross-head or gate 17 of the press. At the lower part 65 of the punch 16 is a cylindrical portion 18, corresponding approximately in diameter to the interior diameter of the finished band, and above the portion 18 is a cylindrical portion 19 of larger diameter, there being an 70 annular shoulder 20 at the lower end of the portion 19. When the washer-like blank is placed in the die and the punch descends, the blank is drawn at its inner part by the portion 18 of the punch and takes up against the 75 shoulder 20 on the punch, by means of which it is pushed entirely through the die, being changed meanwhile from the disk-like shape into a cylindrical band with substantially flat upper and lower edges. In this operation, the blank is drawn continuously from a 80 flat washer shape through a conical shape to a cylindrical one by the application of drawing pressure, acting always from the same side of the blank, and without the necessity of changing the position of the blank in the die. On the upstroke of the punch, the roughly formed band is stripped from the latter by the lower edge 21 of the die opening, the stripping of the band by the die 85 being due to the fact that when the pressure upon the outer surface of the band is removed, the band expands slightly, thus preventing it from passing through the die opening as the punch moves upward. The 90 blank is, therefore, stripped off and falls out of the die through the bottom thereof.

Subsequent to the operation just described, the blank may be placed in another press for the purpose of perfecting its shape, finishing 100 its surfaces more smoothly, and bringing the dimensions more accurately to size. This,

however, is not an essential feature of the present invention.

It will be observed that in the particular form shown, the lower part of the punch is cylindrical for the most part, but has a rounded lower end to draw the washer down into the die. The rigid lateral shoulder 20 is closely adjacent the lower end of the punch and in the particular form shown the 10 distance between said shoulder and the lower end of the punch approximates one-half the minimum diameter of the die.

Various changes may be made in the press construction herein described without departing from the scope of my invention as 15 defined in the claims.

It will be understood that the die and die bed, in the form shown, constitute a die member having an opening therethrough, with 20 an intermediate stripping shoulder, said shoulder being formed by the lower surface of the die proper.

What I claim is:

1. A machine for making projectile bands or the like by drawing a washer-like blank through a die, comprising a die provided with a mouth portion to receive and center the blank, and means, cooperating with the die, to engage the upper edge of said blank 30 and, by pressure thereupon, draw the blank through the die, said means comprising a punch having a cylindrical lower portion with a rigid lateral shoulder closely adjacent thereto, said shoulder exerting pressure upon the upper edge of the blank to force the same through the die.

2. In a machine such as described, the combination of a die having an opening through the same, there being a washer receiving recess at the mouth of said opening, the inner surface of the die having a fillet below said recess joined with the lower edge of the die by a substantially cylindrical portion, a die bed operatively supporting said die, and means, including a punch having a rigid shoulder thereon, for engaging the

upper edge of a washer blank and forcing the same through the die.

3. In a machine such as described, the combination of a die having an opening through the same with a washer-receiving and centering recess at the mouth of said opening, a die bed having an opening through the same, in the upper part of which said die is received, the opening at the lower part of said die bed being of somewhat greater diameter than the lower part of the die opening to cause the lower surface of the die to act as a stripper, and a punch provided with a cylindrical lower portion and a rigid lateral shoulder closely adjacent thereto to draw the washer down into the die and then push it out of the die past said stripper.

4. In a machine such as described, the combination of a die having an opening 65 through the same with a washer-receiving recess at the mouth of said opening, the inner surface of the die having a fillet below said recess joined with the lower edge of the die opening by a cylindrical portion, a 70 die bed having an opening through the same, in the upper part of which opening said die is received, the opening at the lower part of said die bed beneath said die being of somewhat greater diameter than the lower 75 part of the die opening so as to permit the lower surface of the die to act as a stripper, and a punch having a rounded lower end portion to draw the washer down into the die, a cylindrical portion on the punch above 80 such rounded lower end portion, closely fitting the cylindrical part of the die, and a shoulder on the punch immediately above said cylindrical portion thereof presenting a flat surface for engagement with the upper 85 edge of the blank whereby the blank may be forced through the die into stripping position.

In witness whereof, I have hereunto set my hand on the 3rd day of July, 1918.

ALEXANDER W. LIMONT.
